LAVATORY

Stanley F. Korol, Johnstown, Pa., assignor to Crane Co.,
Johnstown, Pa., a corporation of Illinois

Filed Nov. 7, 1962, Ser. No. 72,411

Term of patent 14 years

(Cl. D4—2)

Fig. 1

Fig. 2

Fig. 3

Fig. 4

FIGURE 1 is a rear perspective view of a lavatory showing my new design;

FIGURE 2 is a top plan view turned 180° from FIGURE 1, with a portion broken away for convenience of illustration;

FIGURE 3 is a front elevational view thereof; and

FIGURE 4 is a side elevational view thereof.

I claim:

The ornamental design for a lavatory, substantially as shown.
